CREPING METHOD AND APPARATUS

William H. Cannard, Green Bay, Wis.

Application October 20, 1936, Serial No. 106,683

17 Claims. (Cl. 154—30)

This invention is directed to the production of longitudinal corrugations, or creping, in web or sheet material, having particular reference to the manufacture of crepe paper or similar material wherein pleat corrugations are provided to give elasticity and/or other effects. The invention involves novel apparatus for accomplishing this object and a novel operating method, in the practice of which the proposed apparatus may be employed.

In commercial practice a moving web or sheet of material is usually progressively narrowed and longitudinal corrugations gradually formed incidental to and simultaneously with narrowing, and the operation continued until the corrugations have attained the desired proportions and arrangement. For practical purposes the corrugations or pleats must be relatively numerous and fairly fine, thereby necessitating a substantial transverse crowding of the original web for their production. Any attempt to form the full complement of corrugations within a relatively short longitudinal traverse of the web will be likely to cause lengthwise ruptures in the web and/or tearing at the edges because the material can not be satisfactorily crowded in the various transverse areas to provide sufficient material for formation by the pleating instrumentalities into the full complement of corrugations of the desired form. Because of these practical difficulties, a relatively long machine is required, and the corrugations can not be attained in their desired form, particularly where the web is of substantial width, until the material in the machine has traveled a substantial lengthwise distance.

I have discovered that the corrugating of the material may be carried out to great advantage by dividing the operation into a series of stages under which the material is first transversely crowded into preliminary crinkles, and then re-formed in one or more subsequent stages to produce in the crowded areas the desired corrugated formation.

In the first stage the web may be formed into temporary corrugations or pleats, of a different type than those eventually desired and serving primarily only to narrow the web and produce the transversely crowded condition necessary for the formation of corrugations of another form. In the next stage the temporary corrugations may be completely or in part re-formed or obliterated as having served their purpose, and an entirely new set of corrugations formed in the web which characteristically differ both in number and shape from the original corrugations. This second stage

may provide the final corrugating operation or, as more fully explained in my copending application Serial No. 106,685, filed October 20, 1936, the corrugations produced in the second stage may be re-formed in a further stage into a still different arrangement of corrugations.

It will be understood, in any event, that the purpose of a preceding corrugating stage according to the invention is to provide the necessary crowded or crinkled condition of a web or sheet of material necessary to provide sufficient material widthwise to be formed in the following stage into a predetermined number and form of corrugations. In the preceding stage the preliminary corrugations may be formed to the full width of the web, and the corrugations in the subsequent stage similarly formed to the full width of the web, or only for portions of the width. Again, the preliminary corrugations may be imposed for only a portion of the width of the material, say in the whole central area, and the corrugations in the next stage formed to the full width of the preliminary corrugations and also in the adjoining edge areas not treated in the preliminary stage. The exact procedure followed in this respect will be determined by the degree of crowding necessary to be attained in the preliminary stage to accommodate the entire set of corrugations formed in the subsequent stage and this in turn will be determined by the relative number and size of corrugations in the following stage in relation to the temporary corrugations produced in the preceding stage, or, more specifically, by the relative proportions and numbers of the corrugating instrumentalities in the different stages.

Normally the proposed method will be carried out by producing in the first operating stage preliminary corrugations which are coarser and fewer in number than those eventually desired. In the following stage the relatively coarse corrugations which serve to crowd the web will be re-formed into an entirely new set of corrugations which will be finer both in width and depth than the preliminary corrugations. Thus, one two or more of the finer corrugations may in the second stage be formed in the area originally occupied by a single coarse corrugation. Of course, the greater the number of fine corrugations, the more crowded must be the condition of the web to provide material sufficient for their formation, and the greater must be the material taken up in the bight of the coarse corrugation in order to provide a greater concentration or crowding.

In the apparatus I propose to employ as corrugating means in both the narrowing and main

corrugating units sets of traveling belts in somewhat the arrangement employed in the single stage corrugating machine of my prior Patent No. 1,716,260, dated June 4, 1929. It will be understood, however, that within the broad principles of my invention, other types of corrugating mechanism may be employed in one or more of the combined units. It is entirely within the scope of the present process to use corrugated rolls in one operating unit in combination with belt type corrugating units. The latter arrangement is particularly desirable where the ultimate corrugations are so fine as to be more readily produced by rolls than belts, and such arrangement is specifically covered and more fully disclosed in my related copending application Serial No. 106,685, filed October 20, 1936.

While the present method and machine are directed particularly to the production of longitudinal corrugations in paper or like material, it will be understood that the material may be creped in another direction either prior to or subsequent to the practice of the present invention in order that the material in its final form may be elastic in several directions. Thus, the invention is capable of use in connection with either or both of the principles disclosed in my prior Patent No. 1,595,991, dated August 17, 1926, and Patent No. 1,680,203, dated August 7, 1928.

The present invention contemplates action upon the web or sheet of material while either dry or wet. The longitudinal corrugations produced may be left as formed or crushed into flat crinkles. As more fully hereafter explained, pressing mechanism may be incorporated in the present apparatus following the last corrugating unit, and arrangement may be made to maintain the corrugations and prevent spreading of the web during transit between the corrugating and pressing means.

Other features and objects of the invention will become apparent by reference to the following detailed description of the apparatus as shown in the accompanying drawings.

In such drawings:

Fig. 1 is a top plan view of a corrugating machine constructed in accordance with the invention, certain parts of the underlying operating mechanism being omitted for purposes of clarity;

Fig. 2 is a longitudinal elevation of the machine shown in Fig. 1;

Fig. 3 is a sectional elevation corresponding to Fig. 2;

Fig. 4 is a transverse elevation taken of the left end of the view of Fig. 2;

Figs. 5, 6 and 7 are enlarged fragmentary views of certain parts of the machine shown in Figs. 1 and 2;

Fig. 8 is a fragmentary top plan view corresponding to Fig. 1 involving a somewhat modified construction;

Fig. 9 is a fragmentary sectional elevation corresponding to Fig. 8;

Fig. 10 is a fragmentary end elevation of certain elements in the embodiment of Figs. 8 and 9;

Fig. 11 is a diagrammatic plan view of a modifying construction of the invention and generally corresponding to Fig. 1;

Fig. 12 is a diagrammatic longitudinal elevation of the embodiment of Fig. 11, and also shows additionally one type of system in which the invention may be employed in association with

auxiliary mechanisms in producing corrugating material from a continuous web;

Fig. 13 is a fragmentary end elevation illustrating certain operating parts employed in the embodiment of Figs. 11 and 12, and generally resembling corresponding parts in the embodiment of Figs. 1 and 2 as illustrated in Fig. 6;

Figs. 14 and 15 respectively illustrate more or less diagrammatically the form of the material developed in the preliminary narrowing stage 10 and the subsequent corrugated structure as formed in the second operating stage; and

Fig. 16 illustrates the form of the web where the material, as illustrated in Fig. 16, is subjected to a pressing operation to change the corrugations into flat pleats.

The principles of the apparatus may be understood by reference to the main embodiment as illustrated in Figs. 1 and 2 and the collateral views of Figs. 3 through 7. The reference character 1 designates generally a lower frame designed to be mounted preferably in a horizontal position upon suitable standards (not shown). Spaced above the lower frame is an upper frame which is preferably divided into independent longitudinally adjoining sections 2 and 3. Each of the upper frame sections is adjustably supported in relation to the lower frame to allow the operative relation of the coacting corrugating elements to be varied. There will be a plurality of the supporting and adjusting devices located on each side of the upper and lower frame longitudinally spaced from each other and preferably located at or near the respective ends of the upper frame sections 2 and 3. The general arrangement of such devices may be understood by reference to Figs. 1 and 4. As best shown in Fig. 2 each of these devices will include a supporting member 4 secured to the side of the lower frame 1 through which extends a shaft 5. On the shaft is fixed a supporting element 6 which provides an abutment seating on the upper end of the supporting member 4. The shaft 5 extends upwardly to make screwthreaded engagement with a supporting member 7 affixed to the side of the upper frame member. By rotating the shaft the upper frame will be raised and lowered with respect to the lower frame, and it will be understood that the various devices at the different parts of the frame are independently adjustable so that the two upper frame sections may be adjusted independently of each other and one end of each of the sections adjusted independently of the other end. Such an arrangement is employed so that the corrugating elements may be varied in their operative relation at different parts of their length. To prevent inadvertent changes in the setting of the frame members, the upper end of the supporting shaft 5 is provided with locking means. At the upper end of the spaced cross beams 8 and 9 is secured a plate 10 through which extends a locking bolt 11 engageable with the end of the shaft 5. Once the adjustment is made through rotation of the shaft 5 by the wheel 12 the locking bolt 11 may be brought into engagement with the end of the shaft to fix its position.

The corrugating mechanism of the machine in the present embodiment takes the form of coacting upper and lower sets of traveling endless belts which cooperate to produce corrugations in material as the elements carry the material through the machine. Such type of corrugating mechanism is generally shown and explained in my prior Patent No. 1,716,260, but in the present

instance several stages of belts are employed in carrying out my novel method, under which a preliminary set of corrugations are first formed for the purpose of narrowing the web and then such corrugations converted by other corrugating elements further on in the machine into an entirely new arrangement of corrugations. For purposes of convenience in describing the corrugating mechanism of the embodiment illustrated in the drawings, I will refer to the corrugating instrumentalities which effect preliminary corrugation of the material as the initial narrowing and corrugating unit. The assembly of corrugating elements which act on the web after preliminary operation of the elements of the first unit will be referred to as the further or second corrugating unit, although it may be here explained that it may in some cases be desirable to have the corrugating belts of the first unit extend into or through the second corrugating unit. In any case, however, it will be understood that in the second corrugating unit the assembly of the belts is entirely different in character from the arrangement in the first unit so as to produce an entirely different corrugated effect than attained in the first unit alone.

In the initial unit of the machine the corrugating mechanism will include a set of longitudinally extending parallel elements comprising a series of round endless belts 10 supported in the upper frame section 2. A coacting set of similar belts 11 is supported in the lower frame 1.

The upper belts 10 preferably pass over and are driven by a series of uniformly spaced shives supported on suitable shafts journaled in the sides of the upper frame section 2. At the inlet end of the machine, being at the right in Fig. 1, there is only a single central belt 10 carried by a shive 12. Coacting with said upper central belt are a pair of belts 11 supported by shives 13. The construction of the upper and lower shives and the arrangement of the coacting belts at this stage of the machine is best shown in Fig. 5.

The number of belts is progressively increased at successive points in the initial unit so that the material is gradually narrowed. The number of belts progressively introduced will depend upon the width of the web to be acted upon and it will be clearly understood that the present showing is merely illustrative.

Following the shive 12 is a series of three shives 14 in the upper section, two additional belts 10 being introduced at this point while two additional lower belts 11 are introduced to coact therewith, the latter being supported on a series of four shives 15. It may be here explained that for purposes of clarity the lower belts 11 have been omitted from the plan view of Fig. 1 but are fully shown in Fig. 2.

Spaced rearwardly from the second series of shives are a further series of upper and lower shives 16 and 17 at which point further upper and lower belts 10 and 11 may be introduced.

After the preliminary corrugation of the material has progressed to the desired width, the formation of the initial corrugations may be discontinued, and this is the arrangement illustrated in Fig. 1. A terminal set of upper and lower shives 18 and 19 for the upper and lower belts 10 and 11 is shown following the shives 17. Such shives may in the present embodiment be said to constitute the end of the preliminary operating unit of the machine.

Supporting the respective shives 12, 14, 16 and 18 are a series of shafts 20, 22, 24 and 26 journaled

at their ends in the sides of the upper frame section 2. The lower set of shives 13, 15, 17 and 19 are similarly supported in the lower frame 1 by shafts 21, 23, 25 and 27. By reason of the substantial lateral spacing of the various belts in the initial unit only relatively coarse corrugations will be produced in the material, and this is preferred as it is intended that the preliminary corrugations shall serve primarily to produce the necessary transverse crowding in the material which will enable other corrugations, which require much material widthwise for their formation, to be thereafter produced. It will be evident by reference to Fig. 5 that both by the lateral spacing between the belts 10 and 11, and their amount of vertical overlap as determined by the contour of the belt supporting shives and the adjustment of the upper frame section 2 in relation to the lower frame 1, the degree of crowding of the material may be attained as desired. Because the belts begin at progressive longitudinal points in the initial unit, the narrowing of the web, while gradual, may be effected in a relatively short distance during longitudinal traverse through the machine.

After having been crowded and narrowed by the corrugating instrumentalities of the first unit, the web progresses into the second unit of the machine which includes corrugating elements adapted to produce a different form and arrangement of corrugations. The second unit of the machine in the present instance includes an upper set of traveling belts 30 and a coacting lower set of belts 31. As shown, certain of these belts may be supported at their initial end on shives 44 and 45 disposed upon the upper and lower shafts 26 and 27 of the initial corrugating unit between the respective shives 18 and 19 which carry the belts 10 and 11. Further shives 32, 34 and 36 may be arranged longitudinally of the machine to support the upper belts 30 and similar shives 33, 35 and 37 provided to carry the lower belts 31. As shown in Fig. 2, the respective upper shives 32, 34 and 36 are supported respectively on shafts 38, 40 and 42 journaled in the side members of the upper frame section 3, while the corresponding shives 33, 35 and 37 are fixed to shafts 39, 41 and 43 journaled in the side members of the lower frame 1.

By reference again to Fig. 1, it will be noted that the lateral spacing of the belts in the second unit is substantially smaller than in the initial unit. Two belts 30 are introduced on the shives 44 in longitudinal alignment with the spaces between each two adjacent belts 10 of the initial unit. At the shaft 38 through proper spacing of the shives 32 additional belts 30 are introduced in longitudinal alignment with the belts 10 of the initial unit. It will be understood, therefore, that in the second unit of the machine each of the original coarse corrugations in the material is re-formed into two finer corrugations, this being possible because sufficient material is transversely crowded into the coarse corrugations to allow a series of narrower and shallower corrugations to be formed therefrom. While reference has been made only to the arrangement of the upper set of belts in the second unit, it will be understood by reference to Figs. 6 and 7 that a similar arrangement is made in the lower belts 31 and the shives which carry the same.

In the event coarse corrugations have not been formed to the full width of the web, the previously uncorrugated edge areas may, nevertheless, be provided with the finer type of corruga-

tion. That is to say, the number of upper and lower belts 30 and 31 may be progressively increased at various stages of the second operating unit, and this feature is shown in Fig. 1. Therein 5 additional belts are introduced at the edges of the set through an increased number of shives on each of the shafts 38 and 40. It is assumed, however, that by the time the web has been acted upon by the edge belts which begin at shaft 40 10 corrugation has been effected throughout the complete width. It will be noted by comparing Figs. 1 and 3 that the end shives such as 46 are of smaller diameter than the other shives of the series. This will mean that the edge belts 47 15 of the set will in the first part of their traverse not initially overlap the coacting lower belts 48. By the time, however, the edge belts 47 reach shaft 48 they will engage larger shives and lie in overlapped relation with the lower belts 48. 20 The arrangement for bringing the edge belts 47 and 48 gradually into overlapping corrugating relationship is to avoid tearing at the edges of the material. It will be understood, furthermore, that the general relationship of the sets of upper belts 30 including their edge belts 47 and the sets 25 of lower belts 31 including their edge belts 48 may be adjusted, and entirely independently of the initial section through the adjustment means heretofore described since the two sections 2 and 30 3 of the upper frame can be raised or lowered independently of each other.

It will be noted from Fig. 2 and the comparative views of Figs. 5 and 7 that the shives carrying the corrugating belts in the initial unit 31 are of larger diameter than the shives in the second unit of the machine. As previously explained, coarser corrugations are formed in the initial unit than in the subsequent corrugating unit. As shown in Fig. 7 the upper and lower 40 belts in the second unit will travel substantially in the same horizontal plane whereas in the initial unit, as indicated in Fig. 5, the upper belts 10 will in order to form the deep coarser corrugations travel below the plane of the lower set of 45 belts 11. Hence the shives in the second operating unit may be made of smaller diameter, and of course the planes of the shafts which support the smaller upper and lower shives will be closer together than the planes of the upper and lower 50 shafts which support the larger shives in the initial unit. Further, the initial shives 44, 45 will be smaller than the next shives 32, 34 in the second unit so that the finer corrugating belts 30, 31 will gradually converge into engagement 55 with the material as it leaves the prior corrugation section of the machine.

The traveling belts of the several operating units will be positively driven, and preferably this will be done by driving all of the upper and lower shives of both sections. As shown in Figs. 60 1 and 3, a series of gears such as 50 and 51, one mounted on and rotating a shaft carrying the shives of the upper belts and the other mounted on and rotating the shaft of the lower shives of 65 the next series, will intermesh to drive the corresponding shives. A gear train comprising alternate gears 50 and 51 will extend through the length of the machine as indicated in Fig. 3. At any suitable point power may be imparted to 70 the gear train from a suitable driving mechanism. In view of the fact that the upper and lower sections of the frame are relatively adjustable and change the relation of the respective gears 50 and 51, the gear teeth should be made relatively deep so that they will properly mesh in

any position of the frame parts. The gears 50, 51 of the train which drive the larger shives of the initial section of the machine will be made of such size in relation to the corresponding gears which drive the smaller shives of the second section of the machine that the belts of the several sections will all have the same linear speed so as to carry the material at a constant speed through the length of the machine.

Where, as shown, it is desired to drive all of 10 the upper and lower shives, intermeshing gears 52 and 53 may be secured on the ends of the upper and lower shive shafts. Through this arrangement, since one of the shafts will be positively driven through either the gear 50 or 51, 15 the other shaft and its shives will be also positively driven. The relationship of the gears 52 and 53 to the gears 50 and 51 may be best understood by reference to Fig. 4.

Referring to Fig. 6, because of the large size 20 and slower rotation of the shives 18, 19 which carry belts 10, 11 of the first unit to the shives 44, 45 which carry the belts 30, 31 of the second unit, the larger shives are supported on bushings and free to rotate on shafts 26, 27 while the 25 smaller shives are fixed to the shafts.

Where it is desired to obtain material with the corrugations as formed in the second unit of the machine, no further operation need be performed. In making elastic crepe material, however, it is normally desirable to crush the corrugations into flat crinkles. A third unit may be incorporated in the machine for this purpose, the same comprising in the embodiment of Figs. 1 and 2 a pair of smooth surfaced pressing rolls 54 35 and 55 fixed to shafts 56 and 57. These rolls may be journaled in the upper and lower parts of the frame at the end of the second unit with their plane of contact in general alignment with the web as discharged at shives 36 and 37 from the 40 belts of the second corrugating unit of the machine. By such arrangement the web before discharge will be subjected to the action of the pressing rolls and the corrugations crushed flat. The extent of crushing action may be regulated 45 by adjusting the pressure between the rolls 54 and 55 by regulating the adjustable supports at the outlet end of the upper and lower frame parts 1 and 3. It is obvious, however, that the shafts 56 and 57 of the rolls may be adjustably journaled in the frame so that the pressure may be 50 regulated without in any way affecting the operative relation between the upper and lower corrugating belts which are also supported in the same frame. The pressing rolls will preferably be 55 geared together and driven through the gear train previously described.

In order to hold the corrugations in their proper shape and prevent the material from spreading laterally during transit between the 60 end of the corrugating unit, as may sometimes occur with the arrangement of the crushing rolls as just described, a slightly modified construction may be resorted to such as shown in Figures 8, 9 and 10. In the modification the smooth surface crushing rolls heretofore described may be replaced by other upper and lower crushing rolls 65 58 and 59 journaled on shafts 60 and 61. In such rolls peripheral grooves are provided, and the belts 30 of the second corrugating unit extended 70 around the crushing rolls, being received in the grooves therein as best shown in Fig. 10. The upper and lower belts 30 and 31 overlap each other at the terminal shives 36 and 37, but will 75 gradually diverge and at the bight between the 75

crushing rolls 58 and 59 such belts, by properly proportioning the grooves in the rolls, will just fill the grooves. The provision of the grooves will in this manner not in any way interfere with the effective crushing action of the rolls on the corrugated web.

It will be apparent that the upper and lower belts 30 and 31 will be relatively effective in maintaining the corrugations previously formed 10 and preventing the material from spreading laterally during transit to the crushing rolls.

In some instances it may be desirable to extend the upper and lower belts beyond the point where they both are maintained in operative engagement with the material. In some instances it has been found that the edges of the paper tend to become pinched between the outer sets of corrugating belts, and as the result tend to stick to either the upper or lower set of belts, 20 or more particularly, to the terminal shives around which the belts pass. Tearing of the material often results. This difficulty may be overcome by causing the belts to separate beyond the terminal shives instead of passing 25 abruptly around such shives.

Illustration of this feature of the invention is shown in the further embodiment of Figs. 11 and 12. Here instead of passing directly around the crushing rolls as is the case in the arrangement 30 of Fig. 8, the lower belts extend beyond the crushing roll 58 to a shive 64 and the upper belts 30 are similarly extended beyond the crushing roll 58 to similar terminal shives 65. The latter shives are preferably supported substantially 35 above the general operating plane of the machine. With such arrangement the upper and lower belts 30 and 31 after leaving the crushing rolls pass along divergent paths, preventing the web of material which may be withdrawn as 40 shown in Fig. 12 from sticking to the crushing rolls and thus eliminating any serious danger of tearing. It will be understood that the manner of discharging the material employing the additional shives 64 and 65 may be similarly employed in a machine where the web is to be discharged immediately following the termination 45 of the corrugating operation without the use of the crushing rolls 58 and 59.

As previously mentioned, the preliminary narrowing operation of the first unit may be carried out to substantially the full width of the material, and such an arrangement is also illustrated in the embodiments of Figs. 11 and 12. In its general set-up the arrangement is 55 similar to that found in Figs. 1 and 2. The primary difference is that the number of belts in the initial unit must be progressively increased to a greater width than in the previous embodiment, and this of course requires a greater number of shives in the first unit. In Figs. 11 and 12 the upper and lower shives as diagrammatically indicated by the reference numerals 72 through 79 correspond respectively in position to the shives 12 through 19. Whereas, however, in the 60 prior embodiment the coarse corrugating belts and shives terminate with the shives 18 and 19, in the present embodiment the belts will be extended, with additional belts added at the edges until the web has been narrowed for substantially its full width. Thus, additional upper and lower shives, two pairs 80, 81 and 82, 83 being shown for illustration, are added beyond shives 75 78 and 79. Such an arrangement does not necessitate an increase in the length of the machine but merely increases the length of the initial

corrugating unit with a corresponding reduction in the length of the second corrugating unit. Thus, in effect, the new shives 80, 81 and 82, 83 merely replace the fifth and sixth set of shives 82, 83 and 34, 35 of the machine in Fig. 1. The 5 shives occupying the position of the seventh series in Fig. 1 are the same in the present embodiment and are similarly indicated by the reference numeral 36. In the present embodiment the shives in the position of 82, that is the sixth 10 in the series, will constitute the terminal shives for the coarse corrugating belts of the first unit of the machine. Their shafts will also support the finer set of belts of the second unit. The duplex construction of the shives 82, 83 is illustrated in Fig. 13. In general they conform to the set of shives constituting the fourth in the series in Fig. 1 and illustrated in Fig. 6.

By comparison of Figs. 13 and 6, it will be noted that the large shives supporting the belts 20 of the first unit are somewhat larger than in the machine of Fig. 1. This will result in a somewhat different operative relation between the upper and lower belts calculated to produce a somewhat deeper coarse corrugation. The 25 comparison will make it entirely clear that by changing the size and shape of the belt-supporting shives the type of corrugation formed may be varied substantially. Thus, where the frame adjustment will not produce the desired extent 30 of corrugation, different forms of shives may be employed with satisfactory results.

It will be appreciated from a consideration of the several illustrative embodiments that the material may be formed into a multiplicity of 35 fine corrugations in two operating stages in a relatively short longitudinal traverse. The result of the initial operating stage, as carried out in the first unit of the machine, is indicated in Fig. 14. Therein coarse corrugations only are 40 formed for the purpose of transversely crowding the web. Fig. 15 illustrates the web after passing through the second operating stage, the original coarse corrugations being each re-formed into two new distinct corrugations of finer character and entirely different in shape by the more closely arranged upper and lower belts 30 and 31, of the second unit of the machine. The product, as shown in Fig. 15, will in some cases 45 represent the finished article. Where, however, the crushing rolls are employed to press the corrugations, the latter will be flattened down into the crinkled pleats and will assume the form shown in Fig. 16.

Since the corrugating belts 30 and 31 have 55 been previously described as circular in cross-section, it would be assumed that the corrugations in the product as represented in Fig. 15 would be more or less round. Arrangement is, however, made to obtain the creased rectangular shaped corrugation of the illustrated product 60 through the construction of the shives in the second stage of the machine. By providing the upper and lower terminal series of shives 36, 37 with deep pulley grooves having relatively sharp 65 peripheral shoulders in the machine of Figs. 1 and 2, the material in being pressed between the upper and lower belts will be engaged by the coacting shoulders of the shives and thereby creased. In the preceding series of shives 34, 35, best shown in Fig. 7, the shoulders 84, 85 70 need not be sufficiently high to give a creasing action.

The particular operation of the machine will now be apparent. It may be desired to moisten the material before passing it through the ma- 75

chine and then after leaving the machine conduct it around a drying roll to iron the same and remove the moisture therefrom. This is a more or less conventional set-up and is diagrammatically indicated in connection with the embodiment of the invention shown in Fig. 12. The material either before or after the practice of the present invention may be transversely creped if desired. The invention is particularly applicable to making longitudinally corrugated elastic paper, but also may be used for making light corrugated board and other materials.

I claim:

1. The method of producing crepe which includes forming preliminary coarse longitudinal corrugations in a moving web extending over at least a substantial portion of the width of the web between the side edges, and then forming a finer series of longitudinal corrugations in the web to the full width thereof.

2. The method of producing crepe which includes forming preliminary coarse longitudinal corrugations in a moving web extending over the central portion of the web, and then forming finer longitudinal corrugations in the web in the central coarsely corrugated portion and in the edge portions adjoining the central web portion.

3. In a corrugating machine, the combination of a narrowing unit comprising opposing coacting sets of longitudinally extending spaced elements adapted to support and form longitudinal corrugations in a web passed through the unit between said sets of elements, and a following corrugating unit comprising opposing coacting sets of longitudinally extending elements spaced in different relation to each than the elements in the sets of the narrowing unit and comprising a greater number of forming elements than in the narrowing unit adapted to produce in the web a new set of longitudinal corrugations.

4. In a corrugating machine, coacting upper and lower sets of parallel longitudinally extending spaced corrugating elements arranged to initially corrugate material passed between the coacting sets, further upper and lower coacting sets of parallel longitudinally extending corrugating elements differing in number and spacing from the elements of the prior sets and engageable with the material as corrugated by the elements of the prior sets, at least certain of the elements of said further sets being aligned with the longitudinal spaces between the elements of the initial sets, and means for supporting the corrugating elements of the various corrugating sets.

5. In a corrugating machine, a web narrowing unit comprising coacting sets of spaced traveling belts between which a web of material is supported and longitudinally corrugated during passage through the unit, a corrugating unit comprising coacting sets of spaced traveling corrugation-forming belts adapted to divide the web into finer corrugations than produced in the narrowing unit.

6. In a corrugating machine, a preliminary narrowing unit comprising opposing sets of coacting parallel spaced traveling belts adapted to progressively form coarse longitudinal corrugations in a web of material carried between the sets of belts, and a corrugating unit comprising similar sets of traveling belts arranged in more closely spaced relation than the belts in the narrowing unit and adapted to convert the coarse web corrugations into a new set of relatively fine corrugations.

7. In a corrugating machine, an initial operating unit having opposing spaced apart supports, coacting sets of parallel spaced traveling material-sustaining and corrugating elements on the opposing supports arranged with the corrugating elements of one set coacting with those of the other to transversely crowd and preliminarily corrugate material carried by and between the elements, a further operating unit longitudinally adjoining the initial unit having opposing spaced apart supports, coacting sets of parallel traveling material-sustaining and corrugating elements having a different lateral spacing than the elements of the initial unit and arranged on the opposing supports to carry and corrugate between the elements material received from the initial unit, and means for effecting movement of the elements of the various units.

8. In a corrugating machine, coacting sets of longitudinally extending parallel spaced belts arranged to transversely crowd and preliminarily corrugate material passed between the coacting sets, further coacting sets of longitudinally extending belts adapted to further corrugate therebetween material initially acted upon by belts of the prior sets, at least certain of the belts of said respective further sets being longitudinally aligned with spaces between adjacent belts of the corresponding prior sets, and means for supporting and driving the belts.

9. In a corrugating machine, an initial operating unit comprising coacting sets of longitudinally extending endless belts arranged to corrugate material passed therebetween, the adjacent coacting belts of the sets being spaced substantially offset from each other to form relatively coarse corrugations in the material, means for supporting and driving the belts, a further operating unit disposed end to end with the initial unit comprising additional coacting sets of endless belts arranged to corrugate therebetween the material discharged from the initial unit, the adjacent coacting belts of the sets being more closely spaced than the coacting belts of the initial unit to form relatively finer corrugations in the material, and means for supporting and driving said belts.

10. A corrugating machine including a plurality of opposing spaced apart supports, an initial operating unit comprising coacting sets of spaced traveling material-sustaining and corrugating elements on the opposing supports arranged with the corrugating elements of one set coacting with those of the other to corrugate material carried by and between the elements, a further operating unit longitudinally aligned with the initial unit comprising coacting sets of material supporting and corrugating elements arranged on opposing supports to receive material discharged from the initial unit and form therein new corrugations, the elements in the sets of the subsequent operating unit being greater in number and more closely spaced laterally than the elements of the initial unit, and driving means for the elements of the various units.

11. In a corrugating machine, an initial operating unit comprising coacting upper and lower sets of longitudinally extending laterally spaced corrugating elements arranged to produce longitudinal corrugations passed between the sets, a further operating unit arranged end to end with the initial unit and including other upper and lower sets of longitudinal corrugating elements arranged to further corrugate the material acted upon by the initial unit, means for supporting the

respective sets of corrugating elements, and means for adjusting the operative relation between the upper and lower elements of the respective units, the adjustment means for one unit being operable independently of the adjustment means for the other unit.

12. In a corrugating machine a plurality of spaced apart supports, corrugating means comprising coacting sets of parallel spaced traveling material sustaining and corrugating elements on the opposing supports arranged with the corrugating elements of one set coacting with those of the other set to corrugate material carried by and between the elements, a pair of crushing rolls at the outlet end of the corrugating means for compressing the corrugations of the material into permanent crinkles, said crushing rolls being provided with peripheral grooves receiving the traveling elements of the corrugating means.

13. In a corrugating machine a plurality of spaced apart supports, corrugating means comprising coacting sets of parallel spaced traveling material sustaining and corrugating elements on the opposing supports arranged with the corrugating elements of one set coacting with those of the other set to corrugate material carried by and between the elements, a pair of crushing rolls at the outlet end of the corrugating means for compressing the corrugations of the material into permanent crinkles, said crushing rolls being provided with peripheral grooves receiving the traveling elements of the corrugating means.

14. In a corrugating machine a plurality of spaced apart supports, corrugating means comprising coacting sets of parallel spaced traveling material sustaining and corrugating elements on the opposing supports arranged with the corrugating elements of one set coacting with those of the other set to corrugate material carried by and between the elements, a pair of crushing rolls.

rolls at the outlet end of the corrugating means for compressing the corrugations of the material into permanent crinkles, grooves in the crushing rolls receiving the traveling elements of the corrugating means during crushing of the corrugations, said traveling elements extending beyond the crushing rolls.

15. In a corrugating machine a plurality of spaced apart supports, corrugating means comprising coacting sets of parallel spaced traveling material sustaining and corrugating elements on the opposing supports arranged with the corrugating elements of one set coacting with those of the other set to corrugate material carried by and between the elements, a pair of crushing rolls at the outlet end of the corrugating means for compressing the corrugations of the material into permanent crinkles, grooves in the crushing rolls receiving the traveling elements of the crushing means during crushing of the corrugations, and terminal supports for the respective sets of traveling elements located beyond the crushing rolls and being spaced apart from each other to cause the respective sets of traveling elements to diverge from each other after leaving the crushing rolls.

16. In a corrugating machine, coacting sets of spaced traveling belts adapted to support a web and form therein parallel longitudinal corrugations, and a subsequent corrugating unit having forming means adapted to sub-divide the corrugations formed by the belts into a greater number of new corrugations.

17. In a corrugating machine, the combination of web-narrowing means adapted to produce coarse longitudinal corrugations in a web passing therethrough, and a subsequent corrugating unit comprising coacting sets of traveling belts adapted to re-form the corrugations produced by the narrowing means into a greater number of smaller longitudinal corrugations.

WILLIAM H. CANNARD.
